VIBRATO APPARATUS

Laurens Hammond, Chicago, and John M. Hanert,
Park Ridge, Ill., assignors to Hammond Instrument
Company, Chicago, Ill., a corporation of
Delaware

Application October 10, 1946, Serial No. 702,380

2 Claims. (Cl. 178—44)

1

Our invention relates generally to electrical musical instruments and more particularly to improved capacitative scanning apparatus, particularly for use in musical instruments producing the vibrato effect.

The vibrato effect can be added to music or other sounds, while in the form of electrical signals, by transmitting the electrical signals through an artificial line and scanning the artificial line at a vibrato frequency, as disclosed in the prior patent to John M. Hanert, No. 2,382,413.

The object of the present invention is to provide an improved capacitative scanner for use in such vibrato apparatus.

A further object is to provide an improved means for maintaining an electrical contact with a rotating shaft which will not produce transients in low voltage signals transmitted through the contact.

A further object is to provide an improved capacitor type scanning mechanism which is compact, which will be reliable in operation, and which may be economically manufactured.

Other objects will appear from the following description, reference being had to the accompanying drawings in which:

Figure 1 is an end elevational view of the vibrato apparatus, a portion of the casing being broken away to show the internal construction;

Figure 2 is a transverse sectional view taken on the line 2—2 of Fig. 1, the synchronous motor being shown in elevation;

Figure 3 is a side elevational view of the scanning rotor;

Figure 4 is a plan view of the scanning rotor;
Figure 5 is a sectional view taken on the line 5—5 of Fig. 2;

Figure 6 is a sectional view taken on the line 6—6 of Fig. 5;

Figure 7 is a plan view of the artificial line components and case therefor; and

Figure 8 is a wiring diagram of a portion of the artificial line.

The scanning apparatus comprises a shell 10 closed by a flanged plate 12 (Fig. 2) secured to the shell 10 by screws 14. The scanning device is driven by a synchronous motor 16 having a driving pinion 18 in mesh with a gear 20 mounted for relatively free rotation on a shaft 22. The speed of the synchronous motor 16, and the gear ratio between pinion 18 and gear 20 are such that the gear is driven at a speed of slightly less than 7 R. P. S. or about 400 R. P. M. A pair of flanged hubs 24, 25 are staked to the shaft 22 and form an abutment for springs 26 and 27,

2

the other ends of which engage the gear 20. The springs 26 and 27 thus form a frictional resilient driving connection between gear 20 and shaft 22. The hubs 24, 25 also maintain the gear 20 perpendicular to the shaft 22.

The shaft 22 is mounted in a pair of self-aligning composition bearings 28 and 29, the bearing 28 being suitably secured between a bushing 30 and a bearing support plate 32, the latter being suitably riveted to the wall 12. A disc-shaped thrust bearing is located in the bushing 30. The bearing 29 is similarly clamped between a cup-shaped casing 34 and a plate 36. The bearings 28 and 29 are each provided with an external groove around which threads 38 and 39 are wound, these threads passing through suitable apertures in the wall 12 and casing 34. The threads are made of cotton or similar material and lead to an oil cup, preferably through small diameter tubes. The threads thus form capillary conduits for conveying the oil from the oil cup to the bearings.

A metal hub 40 is secured to the outboard end of the shaft 22 by one or two set screws 41, and has an insulating rotor arm 42 suitably secured to it. A metal rotor arm 44 which is ribbed to render it more rigid, is riveted to the insulating rotor arm 42 and has a plurality of rotor or pickup plates 45 secured thereto. The plates 45 are notched to engage the bent end 43 of the rotor arm 44. The plates 45 are preferably assembled to the middle arm 44 by placing the plates in a suitable fixture and soldering the parts together by heating them in a high frequency electromagnetic field. The rotor is statically and dynamically balanced by a pair of counterweights 46 riveted to the insulating rotor plate 42.

As the rotor rotates, the plates 45 thereof successively pass between groups of stator capacitor plates 48, each group being secured to a mounting bracket 50 in a manner similar to that by which the rotor plates 45 are secured to the rotor arm 44. Each of the brackets 50 is secured to the front wall 12 of the housing by a screw 52, the bracket being insulated from the wall by suitable insulating washers 54. A soldering lug 56 is provided beneath the head of each screw 52 for convenience in connecting wires to the brackets 50. In the embodiment illustrated sixteen groups of stator plates 48 are provided, each group consisting of six plates. It has been found that this arrangement provides sufficient capacitative coupling between the rotor plates 45 and the groups of stator plates 48 to make certain that signals appearing on the stator plates will be impressed

on the rotor plates without excessive loss in signal strength. It will be understood that the groups of stator plates are respectively connected through suitable gang switches to predetermined junction points in the artificial line, as is more fully disclosed in the above mentioned patent No. 2,382,413.

The arm 44 has an offset portion 66 with a bushing 64 held therein, this bushing forming a support for a pin 62 which is pressed into it. The pin 62 is made of a relatively hard, non-tarnishing platinum alloy, such as a 90% platinum and 10% ruthenium alloy or a platinum-iridium alloy, and need be no greater than .032" in diameter. It is located in the bushing 64 so as to be accurately coaxial with the shaft 22.

A pair of studs 68 rivet a flanged casing sheet 70 to the housing 10, the portion of the housing wall around an opening 72 therein being flanged over the sheet 70 to hold it in place against the wall of the housing 10. A housing cover 74 fits over the flanged sheet 70 and is secured thereto by a pair of screws 76.

An insulating mounting strip 78 is secured to the posts 68. A resilient brush arm 80 and a bifurcated spring anchor 82 are secured to the mounting strip 78. The brush arm 80, which is preferably made of a silicon or a phosphor bronze, has a brush button 84, made of a relatively soft carbon or graphite, secured thereto, as by copper plating the carbon and then soldering the copper-plated button to the brush arm. The brush arm 80 is flexed initially so as to press the brush contact 84 lightly against the end of the pin 62, which is spherically rounded to lessen abrasion.

Each of a pair of contactors 86 and 87 has a peripheral groove for receiving a wire harness 88, and is provided with an eccentric hole slightly larger than the diameter of the pin 62. The contactors 86 and 87 are made of pure carbon or graphite. The contactors are maintained in contact with the pin 62 by a pair of springs 90 and 91, respectively (Fig. 5), having one end hooked into loops formed in the harnesses 88 and having their other ends hooked into the bent arms of the spring anchor 82. The connections of the ends of the springs with the anchor 82 as well as with the wire harnesses 88 are soldered so as to assure that the springs will make a good electrical connection between the contactors 86, 87 and the anchor 82. The anchor 82, as well as the brush arm 80, is secured to the insulating mounting strip 78 by a screw 92 and a clamping plate 94. The spring anchor 82 has a soldering lug formed integrally therewith for connection to the output conductor 96 which is surrounded by a shielding sheath 98 (Fig. 1), the latter having a bushing 100 soldered thereto, and the bushing being secured in the housing shell 74 by a screw 102.

Since the holes in the contactors 86 and 87 are eccentric and their harness and springs so arranged as to cause any wear which may take place to be on the side of the hole nearest the center of the contactor, it will be apparent that a great deal of wear may take place before they fail. The platinum alloy pin does not tarnish under normal conditions and since it is substantially harder than the carbon of the brush 84 and contactors 86, 87, substantially all of the wear will take place in the latter elements. Since the erosion products of graphite are naturally finely divided particles of graphite or carbon, they are conductive, and an extremely good electrical

contact is maintained at all times. It has been found that after a short period of use the platinum alloy pin has microscopic depressions or crevices therein filled with particles of relatively soft graphite and the graphite thus acts in part as a lubricant and polishing agent, thereby limiting the wear between the two surfaces and substantially entirely eliminating any wear on the platinum alloy pin. This is a desirable effect since if the platinum alloy pin were abraded to any substantial extent the resulting platinum black, which offers a substantial high resistance, might interrupt the contact and result in the production of noise in the output of the apparatus. The tension applied by the spring arm 80 and the springs 90 and 91 is very small, in the order of a few grams, so that erosion of the graphite will take place very slowly, and since these springs pull upwardly on the pin 62 they lessen the load on the bearings 28 and 29.

Since the holes in the contactors 86 and 87 are initially circular and of substantially the same diameter as that of the pin 62, there is little chance that any particle of dust or lint may work itself between contacting surfaces of these parts, and even after many years of use, when some wear has taken place in the contactors, no trouble is experienced due to dust and lint having collected around the contactors because there are no forces acting upon such particles which tend to draw them between the points of electrical contact. The contact 84 is likewise free from the possibility of having its electrical contact with the end of the pin 62 disturbed by the ingress of dust or lint.

Because of the importance of maintaining an uninterrupted contact with the pin 62, the three contacting elements 84, 86 and 87 are provided, even though one such contact would be sufficient for ordinary purposes. However, by having three contactors, the possibility of interruption of the connection to the pin 62 is so small as to be practically non-existent.

This type of sliding electrical connection is unique in the respect that despite the low contact pressures employed the contact resistance is extremely low and does not vary to a measurable extent. Thus when transmitting a signal of very low voltage through the contacts it has been found that over very long periods of time the signal is faithfully transmitted without the introduction of any transients. The contact arrangement is thus admirably suited for use in the scanner, since the signal picked up by the rotor plates 45 solely by virtue of their capacitative coupling with the stator plates 48, is necessarily of low amplitude.

The elements of the artificial line, schematically represented in Fig. 8, are shown in Fig. 7 as mounted in a box 100 which may be made of wood and which is provided with a pair of channels 101, 102 which extend longitudinally of the box. An intermediate strip of wood 104 separates the channels and has a metallic terminal strip 106 suitably secured thereto. The edges of the channels 101 and 102 are provided with a plurality of vertical extending slots 108 which extend into the wall at an angle of approximately 30°. Slots 110, each in alignment with one of the slots 108 are formed in the center strip 104 and are adapted to receive mounting plates 112 of Micarta or the like. A plurality of coils 116 (inductances L1 to L24) are mounted one on each side of each of the mounting plates 112 with their axes parallel and with a line connecting their centers at sub-

stantially 57° with respect to their axes, thus reducing to substantially zero the magnetic coupling between adjacent coils. Coupling between non-adjacent coils is minimized by their special separation. The coils 116 are clamped to the insulating mounting plates 116 by bolts 123, the ends of which engage porcelain washers 125. The coils 116 are connected in series to form the series inductive path of the artificial line while the junction points between adjacent coils are connected to the terminal plate 106 by one or more shunt capacitors C118 and C119. Various junction points in the artificial line are connected by suitable wires (not shown) to soldering lugs 120 mounted on an insulating terminal strip 122 over a side opening 124 formed in the wall of the container 100. A suitable cover (not shown) closes the top of the box 100 and holds the coils in place.

Adjacent coils 116 are wound in opposite directions thus securing advantageous cancellation of currents induced by external magnetic fields.

To avoid distortion, the inductances L1 to L25 are of the air core type, and thus, due to their open magnetic circuits, have a pronounced tendency to pick up stray magnetic fields such as are produced by power lines and other electro-magnetic components of the instrument. The fact that adjacent coils 116 are wound in opposite directions results in cancellation of such effects. This lack of mutual induction in the coils is furthered by their arrangement in the box 100 whereby they have parallel axes but are axially displaced sufficiently to secure a minimum of flux linkage between them. A terminating impedance coil 126, providing the inductance L25, may likewise be located within the box, being suitably connected between the last coil 116 of the series inductances and the terminal strip 106. The beginning and end portions of the artificial line are schematically shown in Fig. 8. The line may have series inductances L1 to L24 and parallel capacitors C118 and C119 so as to provide twenty-four sections, plus an M-derived termination comprising inductance L25, capacitors C130 and C131, and resistor R132. The circuit and constants of the artificial line are more fully disclosed in the prior Patent No. 2,382,413 and also in Patent 2,509,923, granted May 30, 1950, on the copending application of John M. Hanert, Serial No. 653,195, filed March 8, 1946, now Patent No. 2,509,923, May 30, 1950.

While we have shown and described a particular embodiment of our invention, it will be apparent to those skilled in the art that numerous modifications and variations may be made in the form and construction thereof, without departing from the more fundamental principles of the invention. We therefore desire, by the following claims, to include within the scope of our invention all such similar and modified forms of

the apparatus disclosed, by which substantially the results of the invention may be obtained by substantially the same or equivalent means.

We claim:

- 5 1. A vibrato scanning apparatus comprising a shielding casing, a circular row of stator plates secured to said casing but insulated therefrom, a shaft concentric with the circular row of stator plates, gearing including a frictional and resilient driving connection on said shaft, a shielding housing surrounding the gearing and the major portion of the shaft, a bracket secured to the shaft, a rotor plate secured to said bracket and successively cooperable with said stator plates to form a capacitative coupling therewith, said rotor plate being insulated from the shaft, a metal pin secured to said bracket and electrically connected to said rotor plate, said pin being coaxial with the shaft, and a contactor resiliently held in engagement with said pin.
- 10 2. In a device of the class described, the combination of a generally cylindrical metal casing, a plurality of groups of capacitor plates secured within the casing and arranged in a circular row, means insulating the groups of plates from one another and from the casing, means extending through the casing and insulated therefrom for making electrical connections respectively with the groups of plates, a generally cylindrical bearing housing located within the casing coaxially thereof, a shaft mounted in the housing and having an outboard end extending therefrom, a counterbalanced metallic arm secured to said outboard end of the shaft and insulated therefrom, scanning plates carried by said arm for successive capacitative coupling with said groups of capacitor plates, means to rotate said shaft, a metallic pin secured to said arm in axial alignment with the shaft, and a graphite contactor resiliently held in contact with the pin.
- 15 3. In a device of the class described, the combination of a generally cylindrical metal casing, a plurality of groups of capacitor plates secured within the casing and arranged in a circular row, means insulating the groups of plates from one another and from the casing, means extending through the casing and insulated therefrom for making electrical connections respectively with the groups of plates, a generally cylindrical bearing housing located within the casing coaxially thereof, a shaft mounted in the housing and having an outboard end extending therefrom, a counterbalanced metallic arm secured to said outboard end of the shaft and insulated therefrom, scanning plates carried by said arm for successive capacitative coupling with said groups of capacitor plates, means to rotate said shaft, a metallic pin secured to said arm in axial alignment with the shaft, and a graphite contactor resiliently held in contact with the pin.
- 20 4. In a device of the class described, the combination of a generally cylindrical metal casing, a plurality of groups of capacitor plates secured within the casing and arranged in a circular row, means insulating the groups of plates from one another and from the casing, means extending through the casing and insulated therefrom for making electrical connections respectively with the groups of plates, a generally cylindrical bearing housing located within the casing coaxially thereof, a shaft mounted in the housing and having an outboard end extending therefrom, a counterbalanced metallic arm secured to said outboard end of the shaft and insulated therefrom, scanning plates carried by said arm for successive capacitative coupling with said groups of capacitor plates, means to rotate said shaft, a metallic pin secured to said arm in axial alignment with the shaft, and a graphite contactor resiliently held in contact with the pin.
- 25 5. In a device of the class described, the combination of a generally cylindrical metal casing, a plurality of groups of capacitor plates secured within the casing and arranged in a circular row, means insulating the groups of plates from one another and from the casing, means extending through the casing and insulated therefrom for making electrical connections respectively with the groups of plates, a generally cylindrical bearing housing located within the casing coaxially thereof, a shaft mounted in the housing and having an outboard end extending therefrom, a counterbalanced metallic arm secured to said outboard end of the shaft and insulated therefrom, scanning plates carried by said arm for successive capacitative coupling with said groups of capacitor plates, means to rotate said shaft, a metallic pin secured to said arm in axial alignment with the shaft, and a graphite contactor resiliently held in contact with the pin.
- 30 6. In a device of the class described, the combination of a generally cylindrical metal casing, a plurality of groups of capacitor plates secured within the casing and arranged in a circular row, means insulating the groups of plates from one another and from the casing, means extending through the casing and insulated therefrom for making electrical connections respectively with the groups of plates, a generally cylindrical bearing housing located within the casing coaxially thereof, a shaft mounted in the housing and having an outboard end extending therefrom, a counterbalanced metallic arm secured to said outboard end of the shaft and insulated therefrom, scanning plates carried by said arm for successive capacitative coupling with said groups of capacitor plates, means to rotate said shaft, a metallic pin secured to said arm in axial alignment with the shaft, and a graphite contactor resiliently held in contact with the pin.
- 35 7. In a device of the class described, the combination of a generally cylindrical metal casing, a plurality of groups of capacitor plates secured within the casing and arranged in a circular row, means insulating the groups of plates from one another and from the casing, means extending through the casing and insulated therefrom for making electrical connections respectively with the groups of plates, a generally cylindrical bearing housing located within the casing coaxially thereof, a shaft mounted in the housing and having an outboard end extending therefrom, a counterbalanced metallic arm secured to said outboard end of the shaft and insulated therefrom, scanning plates carried by said arm for successive capacitative coupling with said groups of capacitor plates, means to rotate said shaft, a metallic pin secured to said arm in axial alignment with the shaft, and a graphite contactor resiliently held in contact with the pin.
- 40 8. In a device of the class described, the combination of a generally cylindrical metal casing, a plurality of groups of capacitor plates secured within the casing and arranged in a circular row, means insulating the groups of plates from one another and from the casing, means extending through the casing and insulated therefrom for making electrical connections respectively with the groups of plates, a generally cylindrical bearing housing located within the casing coaxially thereof, a shaft mounted in the housing and having an outboard end extending therefrom, a counterbalanced metallic arm secured to said outboard end of the shaft and insulated therefrom, scanning plates carried by said arm for successive capacitative coupling with said groups of capacitor plates, means to rotate said shaft, a metallic pin secured to said arm in axial alignment with the shaft, and a graphite contactor resiliently held in contact with the pin.
